MAX BERGER AND RUDOLPH WEISBACH, OF SAN FRANCISCO, CALIFORNIA; SAID WEISBACH ASSIGNOR TO SAID BERGER.

NON-REFILLABLE BOTTLE.

1,108,091.

Specification of Letters Patent. Patented Aug. 18, 1914.

Application filed September 2, 1913. Serial No. 787,576.

To all whom it may concern:

Be it known that we, MAX BERGER and RUDOLPH WEISBACH, citizens of the United States, residing in the city and county of San Francisco and State of California, have invented new and useful Improvements in Non-Refillable Bottles, of which the following is a specification.

This invention relates to a non-refillable bottle.

It is the object of this invention to provide a device which may be attached to the neck of a bottle to prevent the bottle being refilled after its contents have been removed, and which device is simple in construction and efficient in operation.

A further object is to provide a valved structure for insertion in a bottle neck, which is so constructed that the valve can not be unseated by jarring or vibrating the bottle and which structure is so formed that wires or other implements can not be introduced therein to dislodge the valve, but which will permit of a free flow of the liquid from the bottle when the latter is in a horizontal or inclined position.

The invention primarily resides in a tube adapted to be placed in the neck of a bottle having an inlet opening at its lower end, normally closed by a loose ball disposed interior of the tube, said tube also formed with a closed upper end provided with discharge perforations, a partition in the tube below its upper end formed with a curved passage leading from one side of the partition to the other, and a pocket in the inner wall of the tube adapted to receive the ball when the tube is disposed in horizontal position.

The invention further consists of the parts and the construction and combination of parts as hereinafter more fully described and claimed, having reference to the accompanying drawings, in which,—

Figure 1 is a vertical section of the invention, as applied and disposed in an upright position. Fig. 2 is a sectional view of the invention, showing it as disposed in an inclined position. Fig. 3 is a horizontal section on the line $a-a$ of Fig. 1.

50 In the drawings A represents the neck of a bottle which is preferably formed with a downwardly convergent inner wall terminating in a shoulder or bead 2 at any convenient point, here shown at the intersection

of the neck with the body portion of the 55 bottle.

The essence of this invention resides in a tube 3 adapted to be inserted in the neck A and cemented or otherwise permanently attached thereto. The tube 3 is cylindrical 60 in form and is preferably made with a tapered exterior wall conforming to the convergent inner wall of the bottle neck A; the lower end of the tube 3 being shaped to abut against the shoulder 2 to support the tube in 65 position in the bottle neck. The lower end of the tube 3 is closed with the exception of a central discharge opening 4 which leads from its underside and terminates in a concaved face 5, which forms a valve seat for 70 a loose ball 6 disposed in the tube 3. A ring or washer 7 of a suitable resilient material surrounds the upper end of the opening 4 and rests on the concave face 5; the washer 7 being shaped on its upper face to conform 75 to the ball 6, and is of such size that its outer marginal edges will extend approximately around the lower half of the ball 6. The washer 7 thus forms a resilient cup or seat for the ball 6 and acts as a suction member 80 to prevent the ball 6 from being unseated when the device is in a vertical position by vibrating or jarring the bottle. The ball 6 is of a diameter slightly less than that of the interior of the tube 3 so as to prevent side- 85 wise movement of the ball when the device is in its vertical position. The upper end of the tube 3 is formed with a reduced portion 8 and is closed at its outer end; a series of outlet or discharge perforations 9 being 90 formed in the side walls of the portion 8. Formed in the tube 3, immediately below the closed upper end, is a partition 10 which converges into a goose-necked central portion 11 having a curved passage 12 therein 95 which opens at one end below the partition 10 and at the other end above the partition 10. Formed in the inner wall of the tube 3, below the partition 10, is an inward projection or shoulder 13 which is provided for 100 the purpose of preventing the ball 6 from striking the partition 10 when the device is inclined. As a means for introducing the ball 6 into the tube 3 before the latter is placed in the bottle neck A, and also to form 105 a recess or pocket in the tube 3 for the reception of the ball 6 after the tube 3 is in position in the bottle neck, an opening 14 of a

diameter corresponding to that of the ball 6 is formed in the wall of the tube 3 immediately below the shoulder 13. The lower wall of the opening 14 is inclined downwardly from the outer face of the tube 3 to its inner face to form a channel 15 for directing the ball 6 into the pocket formed by the opening 14 when the device is disposed in its inclined position.

- 0 In the application and operation of the invention the bottle is filled to a point immediately below the shoulder 2, and the tube 3 containing the loose ball 6 is inserted in the neck A and is permanently held in 15 place therein by cement or in any other suitable manner. The tube 3 is of such length that when positioned in the bottle neck A its upper end will be disposed a sufficient distance below the mouth of the bottle neck 20 so that a cork or other stopper may be applied to the mouth of the bottle in the usual manner.

When it is desired to pour a quantity of the contents of the bottle therefrom, the 25 latter is tilted into an inclined position, as shown in Fig. 2, with the pocket 14 on the underside. The ball 6 will then roll down the channel 15 into the pocket 14 so as to permit the liquid in the bottle to pass 30 through the discharge opening 4 into the interior of the tube 3, from whence it passes through the U-shaped or curved passage 12 and out through the discharge perforations 9.

- 35 For the purpose of insuring a steady flow of the liquid from the interior of the tube 3, a vent opening 16 is formed in the partition 10 adjacent to the lower opening of the passage 12; this vent serving to permit the 40 flow of air into the interior of the tube 3 when the latter is inclined, to displace the liquid removed from the bottle. When the desired amount of liquid has been removed from the bottle and the latter is restored 45 to its vertical position the ball 6 will drop into the resilient cup 7 and effectually close the opening 4 so that liquid can not be introduced into the bottle through the neck thereof. The perforated portion 8 forms 50 an obstruction for the introduction of im-

plements into the tube 3, thereby preventing the ball 6 from being maliciously tampered with. The partition 10 also serves as a further preventive of the introduction of implements in the tube 3, and at the 55 same time serves in conjunction with the goose-neck 11 to form a trap for preventing the free flow of liquid from the outer end of the tube 3 into its interior.

It is manifest that while we have shown 60 the invention as applied to a bottle neck, it is equally adapted for use on other containers from which it is desired to remove the liquid contents and prevent refilling thereof. It is also obvious that while we have shown 65 the device as held in place in the bottle neck by tapering the inner walls of the latter, any other means for attaching the tube and holding it against removal may be employed.

Having thus described our invention, what we claim and desire to secure by Letters Patent, is:

In a non-refillable bottle, a tube insertible in the neck of a bottle having a valve 75 seat on its interior surrounding an inlet opening at its lower end and formed with a closed upper end having discharge perforations therein, a resilient ring on said valve seat, a partition in the tube adjacent to the 80 outer end, an inverted U-shaped passage in said partition, one branch of the passage opening below the partition and the other branch opening above the partition, a loose ball in the tube normally resting on the 85 resilient ring on the valve seat and of a diameter slightly less than the inside diameter of the tube, an inward projection in the tube below the partition to limit movement of the ball, and a pocket in the inside wall 90 of the tube to receive the ball when the tube is disposed horizontally.

In testimony whereof we have hereunto set our hands in the presence of two subscribing witnesses.

MAX. BERGER.
RUDOLPH WEISBACH.
